CLAIM

The ornamental design for a display screen or portion thereof with graphical user interface, as shown and described.

DESCRIPTION

FIG. 1 is a front view of a display screen or portion thereof with graphical user interface according to a first embodiment of the invention.

FIG. 2 is a front view of a display screen or portion thereof with graphical user interface according to a second embodiment of the invention; and,

FIG. 3 is a front view of a display screen or portion thereof with graphical user interface according to a third embodiment of the invention.

The dot-dash broken line represents a display screen or portion thereof and forms no part of the claimed design. The dash-dash broken lines show portions of the graphical user interface that form no part of the claimed design.
